CLAIM

The ornamental design for a display screen or portion thereof with graphical user interface, as shown and described.

DESCRIPTION

1. Display screen or portion thereof with graphical user interface

1: Front

The ornamental design for a display screen or portion thereof with graphical user interface, as shown and described; 1 is a front view of a display screen or portion thereof with graphical user interface showing our new design; the outer perimeter shown in a pair of broken lines in the drawings illustrates a display screen or portion thereof

(Continued)

and forms no part of the claimed design; the dot-dash broken lines define boundaries of the claimed design and form no part thereof.
